UNITED STATES PATENT OFFICE.

JAMES PHILIP HINES, OF BETHLEHEM, PENNSYLVANIA.

TABLE.

1,278,929.

Specification of Letters Patent. Patented Sept. 17, 1918.

Application filed June 21, 1918. Serial No. 241,180.

To all whom it may concern:

Be it known that I, JAMES P. HINES, a citizen of the United States, and a resident of Bethlehem, in the county of Northampton and State of Pennsylvania, have invented certain new and useful Improvements in Tables, of which the following is a specification.

My invention is an improvement in tables, and has for its object to provide a table especially adapted for cashiers' use for making change quickly, wherein the table is provided with grooves or passages for receiving various denominations of coin, and with openings for receiving various denominations of bills.

In the drawings:

Figure 1 is a perspective view of the improved table;

20 Figs. 2 and 3 are sections on the lines 2—2 and 3—3, respectively, of Fig. 1, looking in the direction of the arrows adjacent to the line.

In the present embodiment of the invention the improved table comprises a base plate 1 having supporting legs 2, and a block 3 is arranged upon the base plate, the upper face of the block being horizontal, as shown, and a back plate 4 is arranged at the rear 30 of the block, the said plate in the present instance being integral with the block.

The upper face of the block is provided with grooves or passages 5, the said grooves or passages in the present instance being nine in number and extending from the rear of the table to the front. These passages are adapted to receive rouleaux of coin indicated at 6, each passage receiving one denomination of coin, as, for instance, coins 40 of the value of 1¢, 2¢, 3¢, 4¢, 5¢, 10¢, 25¢ and 50¢. The block is also provided with vertical openings 7 circular in cross section and for receiving bills indicated at 8, the bills having their ends pushed into the openings. The plate 4 is provided with legends indicated at 9 designating the character or denomination of coin, or bill that is to go into the passages and into the openings.

In use, the passages 5 are filled with the 50 coin properly arranged to quickly make

change, as, for instance, in that passage having the designating legend 1¢, pennies are placed one along side the other and the passages are just wide enough to receive a penny and just deep enough to hold the 55 penny approximately flush with the top of the block.

In the passage designated by the legend 2¢, piles of two pennies are placed, and in that passage designated by the legend 3¢, piles of three pennies are placed. In the passage with the designating legend 4¢, piles of four pennies are placed, while in the passage designated by the legend 5¢ piles of nickels are placed. Single dimes are arranged in the single passage designated by the legend 10¢, and piles of two dimes are arranged in that passage having the designating legend 20¢. Each passage is of a width to receive the proper coin and is of 70 a depth such that the uppermost coin of each pile will be flush with the top of the block.

Of the openings 7 there is a series of openings for each denomination of bills, i. e. 75 six openings for \$1 bills and six each for 2's, 3's, 4's, 5's, and 10's. Two one dollar bills may be arranged in the openings marked \$2. or bunches of two \$1., i. e., two ones in each opening. In the openings 80 marked \$3. and \$4. bunches of three ones and four ones are arranged.

In taking 11¢ from a \$20. bill for instance, the cashier will slide into her hand four pennies from the 4¢ passage, and a 10¢ piece 85 from the 10¢ passage, a 25¢ piece from the 25¢ passage, a 50¢ piece from the 50¢ passage, \$4. from one of the openings designated by the legend \$4., a \$5. bill from one of the openings having the designating legend 90 \$5., and a \$10. bill from one of the openings having the designating legend \$10. The openings for the bills are from $\frac{3}{4}$ to $1\frac{1}{2}$ inches deep, leaving about half the bill extending above the top of the table. 95

I claim:

A device of the character specified comprising a table having in the top at one end thereof a series of transversely extending grooves of different depths and having at 100

the other end a number of series of openings, and having a designating legend at one end of each groove and at one end of each series of openings, said grooves being 5 of a depth to receive series of piles of predetermined numbers of coins of pre-

terminated denominations to hold the uppermost coin of each pile with its upper surface in register with the top of the table, and said grooves opening at the front of the 10 table, for the purpose specified.

JAMES PHILIP HINES.
